UNITED STATES PATENT OFFICE.

OLIVER H. ARNOLD, OF WILMINGTON, NORTH CAROLINA.

HAIR-FASTENER.

1,016,466.

Specification of Letters Patent.

Patented Feb. 6, 1912.

Application filed July 12, 1911. Serial No. 638,117.

To all whom it may concern:

Be it known that I, OLIVER H. ARNOLD, a citizen of the United States, and a resident of Wilmington, in the county of New Hanover, State of North Carolina, have invented a new and useful Improvement in Hair-Fasteners, of which the following is a specification.

This invention relates to that type of hair fasteners, either for use as ordinary hair pins, hair ornaments, or the like, which are designed to be prevented from accidental displacement and loss.

The construction and peculiar advantages of the invention are hereinafter fully described and claimed, and illustrated in the accompanying drawings, in which—

Figure 1 is a side elevation of one form of the invention, full lines indicating the normal position of the prongs and dotted lines showing the movable prong deflected as when being introduced into the hair; Fig. 2 is a plan view of the device shown in Fig. 1; Fig. 3 is a transverse section substantially on the line 3—3 of Fig. 2, and Fig. 4 is a view similar to Fig. 2 of a slightly modified form.

Throughout the following description and on the several figures of the drawings similar parts are referred to by like reference characters.

This improved hair fastener comprises a pair of prongs 10 and 11 connecting to each other at 12, or constituting in effect each a continuation of the other.

At 13 is shown an auxiliary prong which, throughout a considerable portion of its length, lies within the prong 11 and in contact therewith. Said prong 13 at some convenient point as at 14, is curved or turned so as to pass outward from within the prong 11 and is thence continued around the bow or loop 15 of the device and is connected in any suitable manner to the main device at 12. The bowed portion 16 of the auxiliary prong is preferably spaced from the bow 15 throughout its length.

As indicated in Fig. 2 the prongs 11 and 13 may be bent laterally from the central plane of the device at 17 and 18. It is to be understood however that the exact form or proportions of the prongs may be varied to a considerable extent without departing from the spirit of the invention. The form

of the device shown in Fig. 4 differs from the other in that the prongs 11' and 13' are so arranged as to slightly cross each other.

The mode of operation of the fastener is as follows: The device is grasped between the thumb and finger so as to apply pressure to the prong 13 at the point indicated by the arrow *a*, causing the auxiliary prong to spring inwardly as indicated in dotted lines. While in this position the fastener is introduced into the hair. Any hair which may be between the opposed portions of the prongs 11 and 13 will be gripped thereby, the elasticity of the device, especially of the auxiliary prong, serving to retain it in engagement with the hair. A portion of the hair, when the device is introduced to its full length, will pass beyond the point 14 and will be retained within the space between the loops 15 and 16, such hair being caused to make a double loop around the prongs as indicated in Fig. 3, due to the curving of the auxiliary prong around the other. The fastener will thus be held securely in place for all practical purposes, but may be easily withdrawn by the fingers in the usual manner.

The device may be made of any material suitable for its purpose, and the novel features of construction may be applied to hair ornaments of a more elaborate design than is illustrated herewith.

Having thus described a preferred embodiment of the invention, what I claim and desire to secure by Letters Patent of the United States is:—

The herein-described hair fastener comprising a pair of prongs connected together in a loop, and an auxiliary flexible prong having one portion thereof in contact normally with the inner face of one of said first mentioned prongs and thence bent laterally and outwardly therefrom and curved around the loop connecting the first mentioned prongs and spaced therefrom, substantially as set forth.

In testimony whereof I have hereunto affixed my signature in the presence of two subscribing witnesses.

OLIVER H. ARNOLD.
